DESIGN FOR A DIRECTION SIGNAL

Everett R. Codde and Bess Bevier Codde,
Oakland, Calif.

Application November 16, 1938, Serial No. 81,141

Term of patent 14 years

To all whom it may concern:

Be it known that we, Everett R. Codde and Bess Bevier Codde, citizens of the United States, residing at Oakland, in the county of Alameda and State of California, have invented a new, original, and ornamental Design for a Direction Signal, of which the following is a specification, reference being had to the accompanying drawing, forming part thereof.

Fig. 1 is a side elevation, which interchangeably forms the rear or front of a direction signal, showing our new design.

Fig. 2 is a top plan view of the direction signal.
Fig. 3 is an end elevation; and
Fig. 4 is a transverse sectional elevation taken on a line 4—4 of Fig. 1.

We claim:

The ornamental design for a direction signal, as shown.
